[57] CLAIM

The ornamental design for an infant carrier, substantially as shown and described.

DESCRIPTION

FIG. 1 is a front elevational view of an infant carrier showing my new design;

FIG. 2 is a rear elevational view thereof; and

FIG. 3 is a right side elevational view thereof. The partial showing of shading indicating a fabric texture is understood to be continuous on the surfaces where shown.

FIG. 1.

FIG. 2.

FIG. 3.
